(57) **CLAIM**

The ornamental design for a flexible camera mounting device, as shown and described.

DESCRIPTION

FIG. 1 is a perspective view of a flexible camera mounting device in full lines with a camera and wire shown in broken lines representing environmental association matter being for illustrative purposes only and forming no part of the claimed invention.

FIG. 2 is a perspective view of the flexible camera mounting device.

FIG. 3 is a right side elevational view thereof, the left side elevational view being a mirror image of the right side view.

FIG. 4 is a front elevational view thereof.

FIG. 5 is a rear elevational view thereof.

FIG. 6 is a top plan view thereof; and,

FIG. 7 is a bottom plane view thereof.
